US00D754130S

(12) **United States Design Patent**
Garcia et al.

(10) **Patent No.:** **US D754,130 S**
(45) **Date of Patent:** **** Apr. 19, 2016**

(54) **OPTICAL SCANNER**

(71) Applicant: **FARO Technologies, Inc.**, Lake Mary, FL (US)

(72) Inventors: **Christopher S. Garcia**, Malvern, PA (US); **Duncan Andrew McArdle**, Downington, PA (US); **Daniel Mockler**, Kennett Square, PA (US); **Charles Pfeffer**, Avondale, PA (US); **Aslan Leo Riza**, Sarasota, FL (US); **Erkan Riza**, Sarasota, FL (US); **Michael Veksland**, Mount Laurel, NJ (US); **Yevgeniy Vinshtok**, Downington, PA (US)

(73) Assignee: **FARO TECHNOLOGIES, INC.**, Lake Mary, FL (US)

(**) Term: **14 Years**

(21) Appl. No.: **29/520,970**

(22) Filed: **Mar. 19, 2015**

(51) LOC (10) Cl. **14-02**

(52) U.S. Cl.

USPC **D14/420**

(57) **CLAIM**

We claim, the ornamental design for an optical scanner, as shown and described.

DESCRIPTION

FIG. 1 is a perspective view of an optical scanner;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

Broken lines and unshaded portions contained within broken lines are not claimed.

References to "side", "top", "rear" and "bottom" in the figure description are not meant to require certain in-use orientation; an optical scanner according to the claimed design may be used in any orientation.

1 Claim, 5 Drawing Sheets
